UNITED STATES PATENT OFFICE.

DAVID S. HITCHCOCK, OF CLEVELAND, OHIO.

DRESS-GUARD ATTACHMENT FOR BICYCLES.

SPECIFICATION forming part of Letters Patent No. 651,568, dated June 12, 1900.

Application filed August 26, 1899. Serial No. 728,564. (No model.)

To all whom it may concern:

Be it known that I, DAVID S. HITCHCOCK, a citizen of the United States, residing at Cleveland, in the county of Cuyahoga and State of Ohio, have invented a certain new and useful Improvement in Dress-Guard Attachments for Bicycles, of which the following is a full, clear, and exact description, reference being had to the accompanying drawings.

The invention relates to a device adapted to connect the inner ends of the cords of a dress-guard with the wheel-axle or bicycle-frame.

15 The object of the invention is to provide a cheap and simple device which will permit all of the guard-cords to be simultaneously tightened or to be disconnected from the machine at their inner ends.

20 The invention consists in the construction and combination of parts hereinafter described, and pointed out in the claims.

In the drawings, Figure 1 is an outer side elevation of the device. Fig. 2 is an inner side view thereof. Fig. 3 is a longitudinal sectional view, and Fig. 4 is a front or edge view thereof.

Referring to the parts by letters, A represents a plate which is adapted for connection 30 with the bicycle-frame. In the specific construction shown it has a hole a, which embraces the rear axle E, and is held thereon by the same nut C which fastens the said axle to the frame. From its lower end the plate extends in a general upward direction. 35 In its upper end is a longitudinal opening a', from the sides of which the slots a² extend in pairs laterally and slightly upwardly. These upwardly-inclined slots are separated by the 40 downwardly-inclined tongues a³, whose inner ends are rounded substantially as shown. The distance across the opening a' between the inner ends of each pair of tongues is great enough to permit the legs of the cord-holder 45 to pass.

The cord-holder B is constructed in its upper part in a suitable manner for the attachment of the guard-cords D. It has two flexible legs b' b', which have outwardly-turned 50 hook-shaped lower ends b² b². In the con-

struction shown this cord-holder is formed of spring-wire bent to form two loops b b, in which the cords are fastened, and the two legs b' b', having the outwardly-turned hook-shaped lower ends b² b². When the two parts 55 are connected together and to the guard-cords and bicycle-frame, the hook-shaped ends b² b² pass through and engage in the outer ends of the slots a² a². When it is desired to disconnect the two parts, the cord-holder is moved toward the lower end of the plate and its legs are pressed toward each other a short distance, whereupon the hook-shaped ends b² b² may be passed through the slots a² a². When it is desired to tighten the 60 guard-cords, the cord-holder is pushed inward. The inclined tops of the tongues force the legs toward each other until they finally pass down between the tongues, whereupon the legs spring outward to the ends of the 70 next pair of slots a² a².

Having described my invention, I claim—

1. The combination of two coöperating members one being a plate adapted for attachment to a bicycle-frame, and the other a 75 cord-holder, one of said members having two legs with bent ends and the other member having a plurality of pairs of openings, said bent ends being adapted to removably occupy the different pairs of openings, substantially 80 as specified.

2. A wire cord-holder bent to form loops at its upper end and having downwardly-extended legs the ends of which are bent, combined with a plate adapted for attachment 85 to a bicycle-frame and having a plurality of pairs of openings, any of which pairs said bent ends may engage, substantially as specified.

3. The combination of a plate adapted for 90 attachment to the bicycle-frame and having a longitudinal opening with a plurality of pairs of inclined slots extending laterally from its sides, with a cord-holder having two legs with outwardly-bent ends for engagement in said 95 slots, substantially as specified.

4. The combination of a plate A having a longitudinal opening a', the plurality of pairs of inclined slots a² extending laterally from said opening and the inclined tongues a³ hav- 100

ing rounded inner ends, with a cord-holder having two flexible legs with outwardly-bent ends for engagement in said slots, substantially as specified.

5. The combination of a plate A having a longitudinal opening with a plurality of pairs of inclined slots extending laterally from its sides, with a wire cord-holder bent to form loops at its upper end and two downwardly-

extended legs having outwardly-turned ends, to substantially as specified.

In testimony whereof I hereunto affix my signature in the presence of two witnesses.

DAVID S. HITCHCOCK.
